BLOWPIPE APPARATUS

James H. Bucknam, Cranford, N. J., assignor to
The Linde Air Products Company, a corpora-
tion of Ohio

Application November 13, 1937, Serial No. 174,335

25 Claims. (Cl. 266—23)

This invention relates to the art of desurfacing metal bodies by means of an oxidizing gas stream, and more particularly to an improved blowpipe assembly for projecting a plurality of gaseous heating and oxidizing jets against a metal body to remove a surface layer of metal therefrom.

The method of eliminating defects from the surfaces of billets, blooms, slabs, and similar semi-finished steel shapes, by applying a suitable wide oxidizing gas stream obliquely to the heated surface, is well known. In the past it has usually been considered necessary to employ for this purpose a plurality of individual blowpipes, especially designed and especially mounted, in order to provide the required gas streams. Such constructions, however, have presented difficulties with respect to close nozzle spacing, number of blowpipes needed, ruggedness of the apparatus, and maintenance of proper relative nozzle positions during operation.

An object of the invention, therefore, is to provide a desurfacing blowpipe apparatus which will effect closer nozzle spacing than has heretofore been the rule. Another object is the provision of such apparatus in a form which will require a minimum number of separate blowpipes for efficient operation. A further object is to provide such apparatus in rugged form adapted to maintain the proper relative nozzle positions during operation of the apparatus.

The above and other objects and novel features of the invention will be apparent from the following description taken with the accompanying drawings, in which:

Fig. 1 is a broken side elevation, partly in section, of a desurfacing apparatus to which one embodiment of the invention is applied;

Fig. 2 is a plan view of a part of the apparatus illustrated in Fig. 1;

Fig. 3 is a cross section taken on the line III—III of Fig. 2;

Fig. 4 is a cross section taken on the line IV—IV of Fig. 2;

Fig. 5 is a plan view of another embodiment of the invention showing an alternative arrangement of the connections and nozzles;

Fig. 6 is an end view of the apparatus shown in Fig. 5;

Fig. 7 is a rear elevational view of the oxygen supply connection of the apparatus shown in Fig. 5;

Fig. 8 is a fragmentary view partly in section showing four desurfacing heads containing blowpipe apparatus according to this invention, ar- 55

ranged to desurface four sides of a rectangular steel billet;

Fig. 9 is an end view of a form of desurfacing nozzle adapted to be used in the blowpipe apparatus of the invention; and

Fig. 10 is a longitudinal sectional view of the nozzle shown in Fig. 9.

The blowpipe apparatus embodying the invention shown in Figs. 1 to 4 inclusive comprises 10 a unitary header block B having openings and passages therein for a heating gas mixture, other openings and passages for an oxidizing gas, such as desurfacing oxygen, all communicating with a series of nozzle openings, an oxidizing gas conduit C discharging into the oxidizing gas passages, and one or more blowpipes W similar to welding blowpipes for mixing fuel and oxidizing gas, discharging into the heating gas openings and passages. A plurality of nozzles N are fastened in the nozzle openings in the forward part 15 of the block B. The block B may be mounted on a desurfacing machine D.

In the drawings, there is shown part of a desurfacing machine D comprising a frame 10, 25 which is connected by vertical pivots 11 and 12 to a support (not shown) for moving the machine over a billet 13. A downwardly projecting arm 14 may carry a shoe (not shown) for contact with a longitudinal vertical face of the billet 20 in order to guide the machine horizontally. Links 15, 15 and 16, 16 pivoted on either side of the frame 10 and to a carrier 17 permit relative vertical movement of the carrier and the support; and springs 18 oppose such downward 30 movement.

The particular desurfacing machine employed forms no part of the present invention. Convenient means must be provided, however, for supporting the block B and for giving it relative 35 movement with respect to the billet 13.

As here shown, a plate 19 is secured to the carrier 17 in any known or convenient manner, for instance in the manner described in applicant's copending patent application for "Apparatus for removing surface metal from metallic bodies", filed April 26, 1937, Serial No. 139,030, now Patent No. 2,203,211, issued June 4, 1940; and the plate 19 supports the block B, the welding blowpipe W, the oxidizing gas conduit C, and 45 certain associated parts for attachment to, or removal from, the desurfacing machine D as a unit. Obviously, these elements might be otherwise attached to the desurfacing machine.

In the embodiment here illustrated, the block 50 B is supported by contact with the inside of a

guiding and protecting means in the form of a box-like shoe 20 which is attached by bolt and nut connections 21 to the lower part of the plate 19. The shoe 20 is adapted to slide upon the upper surface of the metal body 13 during a desurfacing operation, and may be provided with a bearing surface 22 of metal which is abrasion-resistant when subjected to heat. The forward part of the block B rests directly upon the inside of the shoe 20. The rear of the block is provided with a pair of unitary perforated projections 23, 23 which rest in horizontal position upon bosses 24 (only one of which is shown in Fig. 1) formed inside of the shoe. The projections may be bolt-connected to the bosses 24 in well-known manner, thereby fixing the block in the shoe.

The unitary block B has a series of internally threaded nozzle openings 25 in its forward part in which desurfacing or surface metal removing nozzles N are held by nozzle nuts 26, in well-known manner. It is here noted that the shoe 20 is formed in two parts, as fully described in applicant's aforesaid Patent 2,203,211. Thus the forward end wall of the shoe comprises a removable protecting plate 27 which is secured to the rest of the shoe as by bolts 28. The forward part of the main shoe portion and the lower part of the section 27 are so formed as substantially to inclose all of each nozzle N except the discharge ends thereof and protect the same, as fully described in applicant's aforesaid Patent 2,203,211.

As is usual in nozzle connections of the class described, the rear end 56 of the nozzle bears against an annular shoulder in the nozzle opening, thereby sealing an annular chamber 25' from a central gas passage 35, to permit flow of oxidizing gas through the usual axial passage 55 in the nozzle, and separate flow of a heating gas mixture from the annular chamber 25' through a plurality of eccentric passages 57 extending longitudinally of the nozzle. The nozzle openings are formed transversely in line in the front face across the forward part of the block B at a slight angle downwardly with respect to the projections 23 which normally assume a horizontal position when in contact with bosses 24. Furthermore, the nozzle openings are so disposed that the nozzles when in place therein will be inclined relative to each other and inwardly of the block in their forwardly direction, that is to say, at such inclinations that all of the streams of gas issuing from the nozzles will tend to converge toward a central point ahead of the block B. (See Fig. 2.) The symmetrical inclination of the nozzles toward each other, as shown in Fig. 2, may be used when the whole surface of a billet is treated in a single pass, although a parallel arrangement is also preferred for such desurfacing according to the effects desired as will be described hereinafter. When desurfacing a wide slab, however, the nozzles are preferably arranged parallel to each other and all inclined at a uniform angle toward one side.

The block B is constructed with a plurality of separate chambers 29 therein for a heating gas mixture. A separate gas passage 30 connects each annular chamber 25' with the corresponding heating gas mixture chamber. Thus, in the embodiment illustrated in the drawings, three such passages 30 connect the heating gas mixture chamber 29 at the left respectively with the three chambers 25' of the nozzle openings at the left of the block, and four such passages connect the heating gas mixture chamber at the

right respectively with the remaining four nozzle openings. A gas supply opening 31 is provided immediately above the left hand heating gas mixture chamber 29 and a welding blowpipe or the like oxidizing gas and fuel gas mixing device W is coupled into this opening by means of a nut 32 so as to discharge a combustible mixture into the chamber. Similarly, an opening 33 is provided immediately above the right hand heating gas mixture chamber 29, and a second welding blowpipe W is similarly coupled into this opening to discharge a heating gas mixture therein. Thus, the mixture discharged from the first blowpipe will be distributed between three of the seven nozzles which are illustrated in Fig. 2, and the discharge from the second blowpipe will be distributed between the other four of the illustrated nozzles.

A single oxidizing gas manifold chamber 34 is formed in the block B extending transversely thereof rearwardly of the heating gas mixture chamber 29 and is separately connected with each of the nozzle openings 25 by a passage 35 so as to discharge into the central oxidizing gas passage 55 extending axially through each nozzle N. A single internally-threaded opening 36 formed above the oxidizing gas chamber 34 centrally thereof provides means whereby the oxidizing gas conduit C may be coupled into the block B by means of a nut 37 so as to discharge downwardly into and against a wall of the oxidizing gas chamber 34. Thus, oxidizing gas supplied to the chamber 34 from the conduit C will be distributed to all of the nozzles N which are carried by the block B. The chamber 34 comprises in effect two parallel portions joined longitudinally by a narrow or slot-like portion, which formation cooperates to equalize the distribution of oxidizing gas to the nozzles.

40 The oxidizing gas conduit C requires no special support beyond that given it by the nut 37; but each welding blowpipe W, being of heavier construction, is supported from the plate 19 by means of an angle 38, welded or otherwise fixed 45 on the latter, and a bracket 39 similarly fixed to the blowpipe W and connected to the angle by a bolt 40.

Means may be provided for fluid-cooling the block B. As here illustrated, this means comprises an internally-threaded boss 41 (see Figs. 2 and 4) which is formed forwardly of the block B near one side thereof above the nozzle openings, and is connected by a passage 42 to a transversely extending chamber 43 in the lower part 55 of the block. As here illustrated, the chamber 43 is formed by a large transverse bore and a smaller parallel transverse bore in continuous intersection therewith in order to give a chamber of the desired size. Adjacent the opposite end 60 of the chamber 43 from that near which the passage 42 enters it, a passage 44 extends generally upwardly through the block to a transverse chamber 45 above and parallel to the chamber 43; and at the opposite end of the chamber 45 from that near which the passage 44 enters the latter chamber, a cross passage 46 directly communicates with another parallel chamber 47 at a point adjacent one end of the latter, the chamber 47 being formed by a transverse bore in the forward portion of the block B. At the opposite end of the chamber 41, a passage 48 connects the last-named chamber with an internally-threaded boss 49, through which the cooling fluid may be discharged. Thus, a cooling fluid hose having its end coupled into the boss

41 may project cooling fluid through the passage 42 into the chamber 43 adjacent one side of the block B, across the block through the chamber 43 to the passage 44 adjacent the other side of the block into the chamber 45, again across the block to the passage 46, forwardly to the passage 47 across the block, again to the passage 48, and out of the block through the internally-threaded boss 49. A part of the discharge hose 50 may be seen in Fig. 1 coupled into boss 49 by means of a nut 51.

Other means are provided for independently fluid-cooling the blowpipes W. Thus, water may enter the shell 52 which surrounds the conduits of the blowpipe through a nipple 53, circulate through the shell 52, and leave the shell through a second nipple 54.

From the foregoing, the operation of the apparatus will be clear. The block B and the nozzles N attached thereto, all protected by the shoe 20, may be moved over the billet 13 by means of the desurfacing machine D. The links 15, 15 and 16, 16 permit vertical movement of the shoe and block as uneven spots are met on the upper surface of the billet; and the bearing surface 22 on the under side of the shoe protects the latter as it passes over the billet. The nozzles add heat to the surface metal of the billet by projecting against it ignited streams of heating gas mixture, and at the same time remove surface metal from the face of the billet by means of the oxidizing gas stream which they project upon it. The spacing of the nozzles is sufficiently close to produce a substantially continuous oxidizing stream across the entire billet; and the inward inclination of the nozzles maintains the heated oxidized material upon the upper surface of the billet ahead of the gas stream, thereby preheating the surface of the billet and facilitating the work of desurfacing. During operation, the block and the heating blowpipes may be fluid cooled.

If it is desired to use the apparatus for desurfacing a narrower billet, one or more of the nozzle openings may be plugged. When wider surfaces are to be desurfaced in a single pass, the block may be constructed to have a larger number of nozzles which may be supplied with oxidizing gas through a single manifold chamber 34 and a single oxidizing gas conduit C. However, it is desirable to provide a heating gas chamber 29 and blowpipe W for each group of about four nozzles. For example, for 9 or 10 nozzles, it is preferable to provide three blowpipes. A suitable single blowpipe having sufficient heating gas capacity and operating stability can, however, be used to supply all the nozzles of the block.

The desurfacing of wide metal bodies such as slabs may be accomplished by removing the surface metal in a plurality of wide contiguous paths. For such desurfacing, it is preferable to arrange the nozzles parallel to each other and oriented as a group toward one side as in the embodiment shown in Fig. 5. The purpose of such positioning is not only to project the slag away from the desurfaced path and toward the untreated surface when desurfacing a wide body in a series of successive passes, but also for reducing the height of the ridges left between the channels produced by the nozzles. With the nozzle block of the present invention, it is possible to provide a closer nozzle spacing when the nozzles are parallel than could be provided when individual blowpipes for each nozzle were provided.

In the embodiment of the invention shown in Fig. 5, the nozzle block or header B' is relatively narrow and is provided with a separate distributing manifold 134 for the desurfacing oxygen disposed parallel to the rear face of the header B'. The front face of the header is provided with a plurality of bosses 125 having nozzle openings 25 which are arranged to hold the nozzles N secured therein parallel to each other and at a uniform angle toward the left side. This angle may vary according to the effects desired, the greater angle tending to reduce the height of the ridges. The manifold 134 is connected to a series of openings in bosses 132 on the rear face of the header B', which openings are individually connected to the manifold by short connections 135, there being as many connections 135 and bosses 132 as there are nozzle bosses 125.

In Fig. 5, eight nozzle bosses are shown, six 20 being occupied by nozzles N and the last two by imperforate or blank plugs 126, so that the apparatus may be used for desurfacing a surface the width of which is properly covered by the sheet-like stream provided by the six nozzles only. The 25 connections 135 may be welded to the manifold 134 and removably secured to the bosses 132 by union nuts 133 and have passages therethrough which connect with the passages 35 leading through the header B' to the oxygen passage 55 30 of the nozzles. In order that the distribution of pressure in the manifold 134 may be equal for each connection 135, the oxygen is supplied to the manifold at each end thereof in an axial direction by means of conduits 137 which connect 35 the ends of the manifold to a T connection 136 to the side outlet of which the supply conduit C is connected.

The upper face of the header B' is provided with three threaded openings 131 to which blowpipes W (not shown in Figs. 5 and 6) are connected and which communicate with heating gas passages 29 within the header block, as previously described. The three passages 29 corresponding to the three inlets 131 may be arranged to 45 communicate, for example, one with the first three nozzles, the second with the next three nozzles, and the third with the last two nozzle openings. Water cooling passages through the header B' are also provided and may be arranged substantially as described in connection with the form shown in Figs. 1 to 4, inclusive, the water entering at the threaded opening 141 and leaving at the opening 149, both of which are on the upper face of the header. The header B' is also provided with ears 123, similar to the ears 23, for securing the header to the inside of the box shoe 20, as previously described. If desired, an oxidizing gas manifold similar to 50 manifold 134 may be provided in connection with the form of the apparatus described in Figs. 1 to 4, inclusive, when a plurality of oxidizing gas inlets 36 and passages 34 are provided in the block B, a suitable arrangement for example being the provision of the same number 55 of passages 34 as the number of passages 29.

An exemplary method of using the blowpipe apparatus of the present invention for desurfacing the longitudinal sides of a rectangular billet is illustrated in Fig. 8 and constitutes the subject 60 matter of my continuation-in-part application, Serial No. 419,252, filed November 15, 1941. A billet 13 having greater width than height is shown in right section in Fig. 8. The width of its longitudinal surfaces, however, is less than 75 the width of the headers and shoes used, of which

only the nozzle portions are shown in front elevation, the rest being broken away in the interests of clearness. Four shoes 20 are shown in contact with each of the longitudinal surfaces. Each shoe may be supported by mechanism which permits movement thereof toward and away from the respective surface, either individually, or the upper and left-hand shoes may move in unison and the lower and right-hand shoes may move in unison. Suitable desurfacing mechanism for supporting the blowpipe apparatus, for example, may be similar to that shown in the copending joint application of H. W. Jones, J. H. Bucknam, and E. A. Doyle, Serial No. 145,480, filed May 29, 1937 (Patent No. 2,210,921, issued Aug. 13, 1940).

If the shoes were of the correct width to just cover each surface, the forward ends of the nozzles of all four shoes might lie in the same cross sectional plane. However, as shown in Fig. 8, when the shoes are wider than the surfaces, they may be arranged so that one pair is located ahead of the other sufficiently to prevent interference with the offside portions of the other pair. In the figure, the lower and right-hand shoes 20 are in back of the other two shoes and have their front walls 21 in place. The front walls 21 of the upper and left shoes are removed to show the nozzles. It will be seen that the width of the upper surface is fully covered by the streams which issue from the left six nozzles of the upper shoe and the two nozzle openings which are off-side are blanked off by plugs 126. The left-hand shoe has only five nozzles in position to cover the width of the lateral side surface, the other openings being blanked off. The lower and right-hand shoes are similarly arranged. It will be seen also that the nozzles directed toward the upper surfaces are all parallel and oriented toward the left, and the left side nozzles are oriented downward. If the lower nozzles are oriented toward the right and the right side nozzles oriented upwardly, this arrangement may be termed the symmetrical counterclockwise arrangement. A corresponding symmetrical clockwise arrangement would produce substantially the same results.

Other arrangements to suit special conditions may also be used, such as orienting the upper and left-hand nozzles all toward the upper left corner, and the lower and right-hand nozzles all toward the lower right corner. The latter arrangement, for example, may be used when the shoes are mounted in pairs to move in unison in directions at 45 degrees to the faces of the billet, for the shoes may then be arranged symmetrically with the upper left and lower right corners of the billet. In Fig. 8, the upper shoe is displaced to the right, the left shoe upward, the right shoe downward, and the lower shoe to the left because of the orientation of the nozzles which causes the oxygen stream to sweep laterally, the place of impingement of the streams on the surface being to one side of the point of issuance from the nozzles.

The reduction of the height of the ridges between the grooves produced by each nozzle, is obtained by closer nozzle spacing so that more smaller nozzles may be used to cover a given width of surface, and by the orientation of the nozzles to sweep toward one side, which orientation causes each stream to produce a wider and slightly shallower groove. A further reduction of the height of these ridges may be obtained by substituting for the nozzles N, which have cylindrical orifices, nozzles which have a flattened

orifice, i. e., nozzles which have oblong, rectangular or slot-like orifices.

A suitable nozzle is shown at N' in Figs. 9 and 10. The nozzle N' has an axial bore therethrough for desurfacing oxygen, which bore has an inlet portion 55 that receives oxygen from the passage 35 and reduces the pressure thereof, an expanded portion 58 that reduces the velocity of flow to that desired for desurfacing which may be, for example, about 800 feet per second, and an orifice portion 59 proportioned to have substantially the same cross sectional area as the portion 58 and to produce a relatively wide and thin stream of oxygen flowing at substantially equal velocity throughout the width. Preheat passages 57 surround the central bore and conduct the preheating gases from the chamber 25' to the preheat orifices in the forward end of the nozzle.

Such nozzles N' are mounted in the headers B or B' in such manner that the major transverse axes of the orifices 59 are parallel to the surface of the billet or slab to be desurfaced. With the nozzles N' so mounted in a header according to this invention, it is possible to project a practically continuous sheet-like desurfacing stream of oxygen on the surface and remove a layer of surface metal of almost uniform depth therefrom.

For removing surface metal from a wide slab, the shoe supporting device D shown in Fig. 1 may be used and the shoe passed over the work a sufficient number of times to remove the surface metal in a series of contiguous paths with the nozzles preferably oriented away from the surface metal already conditioned. However, it is also contemplated that the entire surface of a wide slab may be removed in one pass by the simultaneous application of a series of nozzle headers with shoes or nozzle headers with other nozzle protecting means, adjacent each other extending completely across the slab. In such an arrangement, all the nozzles would be oriented toward the same side.

It will be clear that apparatus constructed in accordance with the invention may be constructed to effect very close nozzle spacing and will require a minimum number of separate blowpipes for efficient operation, since a single blowpipe may be used to provide a heating gas mixture for a plurality of nozzles. Furthermore, the header, together with the shoe, provides a rugged apparatus adapted for rough use wherein the proper relative nozzle positions are easily and surely maintained during operation. The conduit arrangements for supplying gases and cooling fluid to the blowpipes and nozzle block are very much simpler than the arrangements necessary where individual blowpipes for each nozzle have been used.

The forms of the invention here described and illustrated in the accompanying drawings are presented merely to indicate how the invention may be applied. Other forms differing in detail but not in principle from that here disclosed will, of course, suggest themselves to those skilled in the art.

I claim:

1. Blowpipe apparatus comprising a header block; means for attaching said block to a desurfacing machine; and a plurality of nozzles fitted into a series of openings transversely in line along the front face of said block, said nozzles having their axes lying in a plane through said line and inclined laterally of the forward

direction; said block having therein a plurality of separate chambers for a heating gas mixture, a plurality of separate chambers for an oxidizing gas, separate gas passages connecting each heating gas chamber to a plurality of said nozzles, separate gas passages connecting each oxidizing gas chamber to a plurality of said nozzles, and other passages for cooling fluid extending into, through, and out of said block; in combination with a separate blowpipe discharging into each heating gas chamber in said block; and means for supplying oxidizing gas connected to discharge into each oxidizing gas chamber in said block.

2. Blowpipe apparatus comprising a header block; means for attaching said block to a desurfacing machine; and a plurality of nozzles fitted into a series of openings transversely in line along the front face of said block, said nozzles having their axes lying in a plane through said line and, said block having therein a plurality of separate chambers for a heating gas mixture, separate passages connecting each heating gas chamber to a plurality of said nozzles, separate oxidizing gas passages through said header to each of said nozzles; in combination with a separate blowpipe for supplying heating gas mixture connected to discharge into each heating gas chamber in said block; an oxidizing gas manifold arranged to deliver oxidizing gas at equalized pressures; and connections between said manifold and said header providing communication between said manifold and said oxidizing gas passages.

3. Blowpipe apparatus comprising a header block; means for attaching said block to a desurfacing machine; and a plurality of nozzles fitted into a series of openings transversely in line in said block, said nozzles having oxidizing gas passages terminating in oblong oxidizing gas discharge orifices whose major cross-sectional axes are arranged substantially in alignment so as to produce a substantially continuous sheet-like stream of oxidizing gas, said nozzles also having heating gas passages therethrough; said block having therein at least one chamber for a heating gas mixture, a plurality of passages connecting said heating gas chamber with the heating gas passages of a plurality of the nozzles, oxidizing gas passages in said block connecting with said oxidizing gas passages of the nozzles; oxidizing gas and fuel gas mixing blowpipe means connected to said block for supplying heating gas mixture to said heating gas chamber; and means separate from said blowpipe means connected to said block for supplying oxidizing gas to said oxidizing gas passages.

4. Blowpipe apparatus comprising a header block; a plurality of nozzles fitted into a series of openings transversely in line in said block; and a box-like protecting shoe having a bottom surface positioned for slidably engaging the surface of a metal body and enclosing at least a part of said block and substantially enclosing all of said nozzles except the orifice ends thereof; said block having therein at least one chamber for a heating gas, and separate gas passages connecting such chamber to a plurality of said nozzles.

5. Blowpipe apparatus comprising a header block; means for attaching said block to a desurfacing machine; and a plurality of nozzles fitted into a series of openings transversely in line in said block, said block having therein a plurality of separate chambers for a heating gas, separate gas passages connecting each heat-

ing gas chamber to a plurality of said nozzles, oxidizing gas passages connecting to each of said nozzles; in combination with a box-like protecting shoe on said header block, said shoe having a bottom wall surface for slidably engaging the surface of a metal body, said shoe enclosing at least a substantial part of said block and substantially enclosing all of said nozzles except the orifice ends thereof.

6. Blowpipe apparatus comprising a header block; means for attaching said block to a desurfacing machine; a plurality of nozzles fitted into a series of openings transversely in line along the front face of said block, said nozzles having their axes lying in a plane through said line and inclined laterally of said block to the normal forward direction; said block having therein a plurality of separate chambers for a heating gas mixture, at least one chamber for oxidizing gas, separate gas passages connecting each heating gas chamber to a plurality of said nozzles, and separate gas passages connecting said oxidizing gas chamber to a plurality of said nozzles; means for supplying oxidizing gas to said oxidizing gas chamber; and a blowpipe discharging into each heating gas chamber in said block; in combination with a box-like protecting shoe also attached to the desurfacing machine, said shoe enclosing at least a part of said block and substantially enclosing all of said nozzles except the orifice ends thereof; means for fluid-cooling said block; and other means for fluid-cooling said blowpipes.

7. Blowpipe apparatus comprising a header having a series of openings in a row for accommodating nozzles; a plurality of nozzles fitted into said openings; said header having at least one chamber for a heating gas mixture; a plurality of passages connecting the heating gas chamber with a plurality of said nozzle openings; other passages in said header for conducting oxidizing gas to said nozzle openings; means for mixing oxidizing gas and fuel gas and supplying the resulting heating gas mixture to said heating gas chamber; separate conduit means connected to said header and communicating with said oxidizing gas passages for supplying oxidizing gas thereto; and means enclosing each of said nozzles except the orifice end thereof for protecting said nozzles from direct contact with the surface of a metal body against which the gas streams delivered by said nozzles are applied and for maintaining the orifices of said nozzles at a constant distance from such surface.

8. Blowpipe apparatus for desurfacing comprising a plurality of desurfacing nozzles each having an axial oxidizing gas passage and heating gas passages adjacent thereto, a header having therein a series of openings along the front face thereof for accommodating said nozzles, said nozzles being arranged closely adjacent each other in a row and spaced so that the oxidizing gas streams produced by the oxidizing gas passages of said nozzles merge to form a relatively wide substantially sheet-like desurfacing stream, at least one chamber for a combustible heating gas mixture, passages connecting said heating gas chamber with the heating gas passages of a plurality of said nozzles, a plurality of other passages in said header for conducting an oxidizing gas to the oxidizing gas passages of said nozzles, means for forming and supplying said combustible gas mixture to said heating gas chamber, oxidizing gas supplying means separate from said gas mixture supplying means and

communicating with said oxidizing gas passages, and manifold means for distributing said oxidizing gas to said oxidizing gas passages for flow at substantially the same pressure in each oxidizing gas passage whereby the velocity of flow across the full width of said resulting sheet-like desurfacing stream is equalized.

9. Blowpipe apparatus comprising a unitary header block, and a plurality of nozzles fitted into a series of openings transversely in line in said block; said block having therein a plurality of separate chambers for a heating gas mixture, separate gas passages connecting each chamber to a plurality of nozzles, and a plurality of passages for conducting an oxidizing gas to said nozzles; in combination with a separate oxidizing gas and fuel gas mixing blowpipe connected to discharge into each heating gas chamber; and means independent of said gas mixing blowpipe for supplying oxidizing gas at equal flow pressure to said oxidizing gas passages.

10. Desurfacing blowpipe apparatus comprising, in combination, a header having a series of openings each of which is provided with separate communicating means adapted to deliver a heating gas mixture and desurfacing oxygen to corresponding discharge passages in a desurfacing nozzle adapted to be associated therewith, said header being provided with a manifold chamber for a heating gas mixture, a separate passage connecting each of said openings with said manifold chamber, and other passages in said header for conducting desurfacing oxygen to each one of said openings, conduit means for supplying desurfacing oxygen, and a desurfacing oxygen chamber connected between said conduit means and said desurfacing oxygen passages, said desurfacing oxygen chamber being provided with means for longitudinally distributing said desurfacing oxygen so that it flows at substantially the same pressure in each of the desurfacing oxygen passages.

11. Desurfacing blowpipe apparatus comprising, in combination, a header having therein a series of openings for accommodating desurfacing nozzles, a manifold chamber for a heating gas mixture, a separate passage connecting each of said openings with said heating gas chamber, a manifold chamber for desurfacing oxygen having longitudinal inlet and outlet portions separated by a narrow slot, a separate lateral passage connecting each of said openings with the outlet portion of said desurfacing oxygen chamber, and separate passage means extending through said header for conducting a cooling fluid therethrough.

12. Desurfacing blowpipe apparatus comprising, in combination, a plurality of desurfacing nozzles each having an axial desurfacing oxygen passage and heating gas passages adjacent thereto, a header having therein a series of nozzle openings in each of which one of said nozzles is mounted, means for supplying a heating gas, a passage connecting each of said openings to said heating gas supplying means, and a passage in said header for conducting desurfacing oxygen to each of said openings, conduit means connected to said header and communicating with the desurfacing oxygen passages for supplying desurfacing oxygen thereto, and manifold means having inlets at its opposite ends for longitudinally distributing said desurfacing oxygen to said desurfacing oxygen passages so that it flows at substantially the same pressure in the desurfacing oxygen passage of each of said nozzles.

13. Desurfacing blowpipe apparatus comprising, in combination, a header block having a front face provided with a series of openings, a desurfacing nozzle fitted into each of said openings, the desurfacing nozzles being arranged to perform a common desurfacing operation, said block having therein a chamber for a heating gas mixture, a chamber for desurfacing oxygen having a central inlet, a longitudinal baffle facing said inlet and a plurality of lateral outlets, a gas passage connecting each of said nozzles to said heating gas chamber, and a separate passage connecting each of said nozzles to said desurfacing oxygen chamber through said lateral outlets.

14. Desurfacing blowpipe apparatus comprising, in combination, a header block having a front face provided with a series of openings, a desurfacing nozzle fitted into each of said openings, the desurfacing nozzles being arranged to perform a common desurfacing operation, said block having therein a chamber for a heating gas mixture, a chamber for desurfacing oxygen, a gas passage connecting each of said nozzles to said heating gas chamber, and a separate passage connecting each of said nozzles to said desurfacing oxygen chamber, said desurfacing oxygen chamber and passages comprising manifold means for distributing said desurfacing oxygen so that it flows at substantially the same pressure in each of said nozzles.

15. Desurfacing blowpipe apparatus comprising, in combination, a header block having therein a series of openings for accommodating desurfacing nozzles, at least one heating gas mixture chamber, a passage connecting each of a plurality of said nozzle openings with said chamber, and a separate passage for conducting desurfacing oxygen to each of said openings, a blowpipe connected to discharge a mixture of oxidizing gas and fuel gas into said chamber, and means independent of said blowpipe for supplying desurfacing oxygen to each desurfacing oxygen passage at substantially the same flow pressure comprising a manifold provided with inlet and outlet means for longitudinally distributing oxygen uniformly therein.

16. Desurfacing blowpipe apparatus comprising, in combination, a header block having a series of openings arranged in line, a plurality of nozzles fitted into said openings, said block having therein a plurality of separate chambers for a heating gas mixture, separate gas passages connecting each of said openings with a selected one of said heating gas chambers, said header having a separate desurfacing oxygen passage communicating with each of said nozzles, a blowpipe connected to discharge into each of said heating gas chambers, and manifold means associated with said header block for supplying desurfacing oxygen to the desurfacing oxygen passages at equalized pressures, whereby said desurfacing nozzles are adapted to perform a common desurfacing operation.

17. Desurfacing blowpipe apparatus comprising, in combination, a header block, and a plurality of desurfacing nozzles fitted into a series of openings arranged in line along the front face of said block, said nozzles having their axes lying in a plane including said line and being inclined laterally, said block having therein a plurality of separate chambers, separate gas passages connecting each of said chambers to a separate group of said nozzles, and a separate blowpipe

adapted to discharge a heating gas mixture into each of said chambers.

18. In desurfacing apparatus, a multiple nozzle header comprising, in combination, a block having separate manifold chambers for desurfacing oxygen and heating gas respectively, a plurality of desurfacing nozzles carried by said block and arranged in line in fixed angular relation, said nozzles each having a desurfacing oxygen discharge passage and a heating gas discharge passage, and said manifold chambers having a desurfacing oxygen passage and a separate heating gas passage communicating with the corresponding discharge passages in each nozzle, the longitudinal axes of said desurfacing oxygen passage and heating gas passage being disposed at an angle to each other within said block.

19. A scarfing torch comprising an elongated block with a plurality of large orifices opening through a face of the block for directing oxygen jets against the surface of a metal body to be scarfed, said orifices being spaced along the length of the block, and smaller orifices opening through said face of the block around each of said oxygen orifices and communicating with distributing passages through which fuel gas is supplied to the smaller orifices for preheating flames.

20. A scarfing torch comprising a head having an elongated face with a row of orifices extending lengthwise of the face and from which scarfing jets of oxygen are directed against the surface of a metal body, and other orifices opening in said face and from which preheating fuel-gas flame jets are directed toward the surface of the metal body, one or more of the preheating jets being located under each of the oxygen jet orifices, said other orifices communicating with distributing passages in said head through which fuel gas is supplied to said other orifices for preheating flames.

21. Blowpipe apparatus comprising an elongated head with a plurality of large orifices opening in a face of the head for directing oxygen jets against a surface of a metal body to be conditioned, said orifices being spaced along the length of said face of the head, distributing passages in said head for supplying oxygen to said large orifices, and smaller orifices opening in said face around each of said oxygen orifices and communicating with distributing passages in said head through which fuel gas is supplied to the smaller orifices for preheating flames.

22. A blowpipe apparatus for scarfing a metal workpiece comprising an elongated head having a face and a plurality of oxygen jet orifices opening through said face for delivering scarfing jets obliquely against and along a workpiece, said orifices being at spaced points along the length of said face and close enough together to remove surface metal from contiguous areas of the workpiece; distributing passages in said head through which oxygen is supplied to said orifices; and a supporting bearing with a surface in a fixed relation to said face of the elongated head.

gated head and in such angular position with respect to said face that when said bearing is in surface contact with an area of the surface of the workpiece, said orifices are in working relation to said body.

23. Blowpipe apparatus comprising a header block having a front face; a row of nozzles fitted to a series of openings transversely in line along said front face, said nozzles being adapted to discharge oxidizing gas streams and heating flames against a surface of a metal body, said block having therein passages for supplying oxidizing gas to said nozzles and other passages for supplying fuel gas to said nozzles; and guiding and protecting means secured to said header block including a bearing surface adapted to engage said surface of the body, and a nozzle protecting portion in front of said front face, said nozzle protecting portion having openings therethrough into which said nozzles project, and said bearing surface being arranged at an acute angle to said nozzles and at a predetermined uniform spacing from the discharge ends of said nozzles.

24. Blowpipe apparatus comprising a header block having a front face; a row of nozzles fitted to a series of openings transversely in line along said front face, said nozzles being adapted to discharge oxidizing gas streams and heating flames against a surface of a metal body, said block having therein passages for supplying oxidizing gas to said nozzles and other passages for supplying fuel gas to said nozzles; and guiding and protecting means secured to said header block including a bearing surface adapted to engage said surface of the body, said bearing surface being arranged at an acute angle to said nozzles and at a predetermined uniform spacing from the discharge ends of said nozzles; and a removable protecting plate disposed in front of said front face and having openings into which said nozzles project.

25. Blowpipe apparatus comprising a header block; means for attaching said block to a desurfacing machine; and a plurality of nozzles fitted into a series of openings transversely in line in said block, said nozzles having oxidizing gas passages terminating in oblong oxidizing gas discharge orifices whose major cross-sectional axes are arranged substantially in alignment so as to produce a substantially continuous sheet-like stream of oxidizing gas, said nozzles also having heating gas passages therethrough; said block having therein a plurality of passages for conducting a heating gas to the heating gas passages of said nozzles and a plurality of oxidizing gas passages for conducting oxidizing gas to said oxidizing gas passages of the nozzles; and a shoe on said block for protecting and holding said nozzles in closely spaced alignment, said shoe having a front wall provided with openings into which said nozzles extend, and a surface portion at a predetermined uniform spacing from the discharge ends of said nozzles for preventing contact of said nozzles with a work surface.

JAMES H. BUCKNAM.
